UNITED STATES PATENT OFFICE.

WILLIAM F. MORRISON, OF VALLEJO, CALIFORNIA.

RAIL-CLAMP.

1,375,310.

Specification of Letters Patent. Patented Apr. 19, 1921.

Application filed January 3, 1921. Serial No. 434,439.

To all whom it may concern:

Be it known that I, WILLIAM F. MORRISON, a citizen of the United States, residing at Vallejo, in the county Solano and State 5 of California, have invented new and useful Improvements in Rail-Clamps, of which the following is a specification.

This invention relates to an improved rail-tie construction in which the body of 10 the tie is constructed of concrete and the means for securing the rails to the tie is formed of metal the two being peculiarly associated and so relatively arranged and constructed that a simply constructed, inexpensive, durable strong and reliable tie is 15 provided.

The primary object of the invention is to provide a tie of the character described which will positively hold the rails against 20 spreading and which will be easy to assemble, there being rail clamping means of simple, strong and inexpensive construction, and tie reinforcing means which latter will provide adequate strength and resiliency in 25 the tie.

Another object is to provide in a tie of the character described a rail clamp which is small, compact, consists of few parts, is capable of being readily and easily 30 assembled and disassembled and which provides maximum holding action against spreading of the rails.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be 45 embodied in a plurality of forms.

Referring to the drawings:—

Figure 1 is a fragmentary top plan view of a section of a railway track at a point, showing the ties of my invention as they 50 would appear when in use.

Fig. 2 is a side elevation of the tie and clamp at one end of the tie showing the rail in section.

Fig. 3 is an enlarged fragmentary sectional view taken longitudinally through

one end of the tie and showing the rail clamp in side elevation and in section.

Fig. 4 is a longitudinal sectional view through the tie.

Fig. 5 is a perspective view of the rail 60 clamp member.

Referring to the present embodiment of the invention as shown in the accompanying drawing, the tie embodies a concrete body 1 having double arched or bowed reinforcing rods 2 embedded therein and extending longitudinally thereof from end to end. The arch 3 of said rods has its highest point or center disposed near the upper side of the tie at one end and the arch 4 is 70 correspondingly arranged at the other end of the tie, the center arch 5 thus provided, being inverted and with its lowest points near the under side of the tie and centrally of the ends of the tie. Straight reinforcing rods 6 extend between and engage the arches 3 and 4 on opposite sides of the arches and extend horizontally above the inverted center arch 5. These rods add strength to the reinforcement and increase 80 the resiliency of the tie as a whole.

Similar straight rods 7 extend between each of the arches 3 and 4 and abut opposite lower end portions of said arches as shown in Fig. 4.

These reinforcing rods 2, 6 and 7 are designed and relatively arranged to provide for maximum reinforcing action and resiliency without necessitating the use of a multiplicity of reinforcing members and 90 thus provide for a cheaper and lighter tie which is protected against cracking and chipping as well and made strong, more durable and suitably resilient.

In the upper side of the tie near each 95 end thereof a rectangular recess 8 is formed and said recess receives a flat metal rail supporting plate 10 which plate is flush on its upper side and on opposite sides with the top and sides of the tie. Formed in each 100 plate near each end thereof is a rectangular recess 11 adapted to receive a rail clamping member 12. The member 12 has a rectangular lug 13 on its lower side and said lug fits snugly within the recess so as to prevent 105 slipping of the clamp members. A bolt 14 is inserted through the plate at each recess and extends through each recess with its threaded end disposed well above plate 10. The head 15 of the bolt is anchored in the 110

concrete body of the tie below the under face of the plate 10. The clamping members 12 have central apertures 16 through which the bolts extend. Nuts 17 are turned 5 on the bolts and hold the members 12 in place. The outer ends of said members 12 on the upper side thereof are cut away as at 18 and slope or taper outwardly so as to reduce the weight of said member. The 10 inner ends of the members 12 have beveled under faces 19 adapted to engage the flanges 20 of the rails 21.

At the joints of the track two ties, one 15 on each side of the joint as shown in Fig. 1 are used. The fish plates 21' in angle iron form extend from one tie to the other and lie upon the base and shank of the rails. Each fish plate is cut away on its lower 20 outer edge to provide a notch or outwardly opening recess 22 in which the member 12 engages. The fish plates extend beyond the flanges or bases of the rails and the notches or recesses permit of the engagement of the member 12 in overlapping relation upon the 25 bases or flanges of the rails. The fitting of the clamp members 12 in the notches 22 insures the positive and secure holding of the clamp members in place. The lug 13 abuts the edge of the rail flange or base and is in 30 part received in the notch of the fish plate. It will therefore be seen that the rail tie of this invention consists of but few parts and is inexpensive and easy to set up or take down for the plates 10, members 12, and 35 fish plates 21'. These parts are more securely and rigidly held in place and permit of light construction and a complete arrangement of the parts of the tie.

The centers of the arches 3 and 4 of the 40 reinforcing rods 2 are engaged with the under sides of the rail supporting plates 10 and in this way the desired resiliency is

provided together with strength and durability, inasmuch as the strains and loads from the rails are taken up in part by said 45 rods as well as by the tie itself.

While I have shown only one of the reinforcing rods and its coöperating parts it is to be understood that any number of said reinforcing elements may be used. 50

I claim:

1. In combination with a rail tie, a rail and a fish plate a part of which extends over the base of the rail and is notched at its outer edge, of a rail supporting plate on 55 the tie provided with a recess in its upper side, a rail clamping member engaging in the notch in said fish plate, a lug on the under side and between the ends of said member being engaged in said recess, a bolt 60 extending through the plate, the lug and said member, and a nut threaded on the upper end of said bolt, said lug having engagement with the adjacent outer edge 65 of the base of the rail.

2. In combination with a rail tie, a rail and a fish plate a part of which extends over the base of the rail and is notched at its outer edge, of a rail supporting plate on 70 the tie provided with a recess in its upper side, a rail clamping member engaging in the notch in said fish plate, a lug on the under side and between the ends of said member being engaged in said recess, a bolt 75 extending through the plate, the lug and said member, and a nut threaded on the upper end of said bolt, said lug having engagement with the adjacent outer edge 80 of the base of the rail, said fish plate portion extending beyond the outer edge of the rail base and receiving said lug in the end in the notch formed therein.

WILLIAM F. MORRISON.
